UNITED STATES PATENT OFFICE.

ALVIN V. ROWE, OF GALESBURG, ILLINOIS.

STEEL FENCEPOST AND ANCHORING MEANS.

Application filed October 12, 1922. Serial No. 594,005.

To all whom it may concern:

Be it known that I, ALVIN V. ROWE, a citizen of the United States, a resident of Galesburg, in the county of Knox and State 5 of Illinois, have invented new and useful Improvements in Steel Fenceposts and Anchoring Means, of which the following is a specification.

This invention has reference to improvements in steel fence posts and to the anchoring means therefor, and it has for its principal object to so construct a steel post of the T type as to strengthen the same; provide a new and improved fastening means 15 for the fence wires, and also to provide for fastening the anchoring plate without riveting.

The invention has for a further object to emboss the face of the post during the 20 rolling or forming thereof, or by punching, or in any other suitable manner; such embossed portions being preferably arranged in pairs, one at either side or edge of the face of the post, and suitably spaced 25 throughout the length of the post.

A further object of the invention is to provide the face of a T post with a double row of outwardly embossed portions suitably spaced at either edge of the post; each 30 embossed portion providing a corresponding depression on the opposite face of the post, such embossed portions providing a rest or seat for a fence wire adapted to be held in place by a staple, one end of which is 35 bent over an edge of the post and pressed into an embossed depression to lock the same in place, the body of the staple being passed diagonally across the fence wire above an embossed portion and bent back and over 40 the edge of the rib or web of the post.

The invention has for a further object to construct a T steel fence post with pairs of embossed portions spaced in a suitable manner throughout the length of the post, 45 each embossed portion providing a corresponding depression on the opposite face of the post; and in the provision of an anchoring plate attachable to the front face of the post and provided with an opening 50 or openings forming a seat or seats for embossings coincident therewith on the post, and also with lips or wings adapted to be bent over the opposite edges of the face of the post and back against the rear of the 55 face of the post and impressed in the de-

pressions of the embossings to securely lock the anchor plate in position.

That the invention may be more fully understood, reference is had to the accompanying drawings forming a part of the 60 description, illustrating a preferred embodiment of the invention, in which:

Figure 1 is a front face view of a T steel fence post, partly broken away, embodying my invention, such post shown 65 provided with an anchor plate, and also with fence wires attached to the post in accordance with my invention;

Figure 2 is a detail in elevation showing the post and anchor plate, being a face view 70 opposite to that shown in Figure 1;

Figure 3 is a cross-section as the same would appear, if taken on the line 3—3 Figure 2;

Figure 4 is a cross-section as the same 75 would appear, if taken on the line 4—4 Figure 1, the line wire of the fence being shown in dotted lines;

Figure 5 is a perspective view of a section of the post designated by the line 5—5 80 Figure 1;

Figure 6 shows a modified anchor plate and its attachment to the post;

Figure 7 is a face view of the post and anchor plate opposite to that shown in 85 Figure 6;

Figure 8 is a cross-section in plan as the same would appear, if taken on the line 8—8 Figure 7;

Figure 9 is a rear face view of a modified 90 post structure, wherein the embossings at the opposite edges of the post are in staggered relation;

Figure 10 is an edge view of the post shown in Figure 9, and 95

Figure 11 is a perspective view of a portion of the post shown in Figures 9 and 10.

Like characters of reference denote corresponding parts throughout the figures.

Structural tee (T) shapes, are well known 100 and have proven very useful as fence posts in the support of wire fence fabrics and poultry nettings. Attempts have been made to overcome the punching of the face of the posts through which the securing staples have been inserted, to prevent the weakening of the post while at the same time strengthen the same; and also to provide an effective means for fastening the anchor plate without weakening the structure and 110

without adding to the cost of production, but none such have embodied the structural advantages of my invention, so far as I am aware.

5 In the drawings, 1 designates a T steel post having the usual face plate 2 and the rib or web 3. The lower end being pointed or tapered, as at 4. So far as described, the post does not differ from the usual and 10 well-known structural tee (T).

The face plate 2 of the post is provided with a plurality of sets of embossed portions 5, preferably arranged in pairs, one embossing at either side or edge of the face 15 plate, and the pairs of embossings suitably spaced throughout the length of the post. These embossed portions 5 may be provided during the rolling or forming of the structural shape, and while the metal is hot, or 20 immediately following such rolling or forming of the shape, or by punching, or in any other convenient and practical manner. Each embossed portion 5 is formed by pressing out the metal from the rear of 25 the face plate 2 which provides depressions or seats 6 in the rear of the face plate coincident with each embossing, see Figures 4 and 5. By embossing the face plate of the post in the manner shown, several important 30 things are accomplished. First, the post is materially strengthened without rolling into the shape any additional material at an added expense in the cost of material. Second, seats or rests are provided for the 35 line wires of a fence, which, aided by the staple fastening means prevent lateral and endwise movement of the fence wires on the post, and thirdly, the depressions formed by the embossing receive ends of staples for 40 fastening the wires to lock the staples in position on the post, and also members on the anchor plate for locking the latter in position on the post.

For purposes of illustration, I have shown 45 in Figure 1 a fence fabric fastened to the post; such fabric including a plurality of line wires A and stays or picket wires B connected thereto, being the usual form of open square mesh fencing. The line wires 50 A lie across and in juxtaposition to the front of the face plate 2, see Figure 4 and rest on a pair of the embossed portions 5 at either edge of said face plate. Staples 7 are employed to fasten the wires A on 55 the post and their manner of attachment is best seen in Figures 1 and 4, wherein one end 8 of the staple is bent over an edge of the face plate 2 and pressed into a depression 6 of an embossed portion 5, to lock the 60 end of the staple in position. The body of the staple is then carried diagonally across the face of the post and across the line wire A and the staple bent over the wire A and around the edge of the post, above an embossed portion 5 so as to hold the wire A

down on the embossed portions 5 and to prevent lateral and endwise movement of such wire. The end of the staple is then carried back and bent over or around the edge of the rib or web 3, of the post, see 70 Figure 4.

In Figures 9, 10 and 11 the embossed portions 9, on the face of the post are of slightly different formation and staggered relatively to each other on the opposite edges of the 75 face plate.

The anchor plate is designated 10 and may have the shape shown in the figures, or be of any other desired shape. In the preferred form, in which it is shown in Figures 1, 2 80 and 3 it is stamped or formed with a plurality of transversely arranged parallel spaced openings 11, the metal from which provide the lips or wings 12 which are bent over and down against the rear face of the 85 face plate 2 and on either side of the rib or web 3, see Figures 2 and 3. The openings 11 are so spaced relatively to each other, that when the anchor plate 10 is applied to a post certain of such openings will 90 receive embossed portions 5 on the post, see Figures 1 and 2 which will permit the anchor plate to lie flat against and across the face of the post, and the lips or wings 12 that lie coincident with depressions 6 of the embossed portions 5 projecting within 95 the openings 11, are pressed into such depressions 6 to lock the anchor plate against up or down movement on the post. I prefer to apply the anchor plate hot, so that when 100 it cools the shrinkage will aid in a tight grip of the anchor plate to the post; however, it may be applied when cold, with good results.

In Figures 6, 7 and 8 the anchor plate, 105 instead of having a number of openings, is provided with one large opening 13 long enough to span two sets or pairs of embossed portions 5, the upper edge 14 of the opening embracing one pair of embossings and the lower edge 15 of the opening embracing another pair of embossings. The metal from such opening 13 providing opposite lips or wings 16, see Figures 7 and 8 adapted to be bent over and to embrace the opposite embossed edges of the face plate 2 and portions of such lips or wings are pressed into the 110 depressions 6, as at 17, see Figure 7 to lock the anchor plate in position on the post.

What I claim is:—

1. A fence post comprising a structural T shape, the face plate of which is provided with spaced embossed portions along its opposite edges, an anchor plate having means complementary to said embossed portions to permit said anchor plate to lie flat against the face of said post, and means on the anchor plate to embrace portions of said post.

2. A fence post comprising a structural T

shape, the face plate of which is provided with embossed portions on one face of the plate and corresponding depressions on the opposite face of the plate, an anchor plate having means complementary to said embossed portions to permit said anchor plate to lie flat against the face of said post, and means on the anchor plate to embrace the opposite side edges of the face plate of the post and pressed into the depressions on said post to lock the anchor plate in position.

5 In witness whereof, I have hereunto affixed my hand and seal this 9th day of October, 1922.

ALVIN V. ROWE.
